P. LE R. McCALL

PAPER CONE AND ART OF MAKING SAME

Filed Oct. 17, 1925

Inventor

Peter Le Roy McCall,
By Prentiss, Stone & Boyden,
Attorneys

Patented Mar. 23, 1926.

UNITED STATES PATENT OFFICE.

PETER LE BOY McCALL, OF ROCKINGHAM, NORTH CAROLINA.

PAPER CONE AND ART OF MAKING SAME.

Application filed October 17, 1925. Serial No. 63,096.

To all whom it may concern:

Be it known that I, PETER LE ROY Mc-
CALL, a citizen of the United States, residing
at Rockingham, in the county of Rich-
mond and State of North Carolina, have in-
5 vented certain new and useful Improvements
in Paper Cones and Art of Making Same,
of which the following is a specification.

This invention relates to cones and tubes
10 such as are used by cotton mills for winding
yarns, and more particularly to cones made
from substantially sector shaped paper
blanks.

In making such cones, it has heretofore
15 been customary to employ a rotary conical
mandrel, such mandrel having a longitudinal
slot in its surface, into which slot one
edge of the sector-shaped blank is inserted,
so that, as the mandrel is turned, the blank,
20 having been previously coated with adhe-
sive, is wound upon the mandrel to form a
cone.

Before such a cone is marketable, the ends
25 must be trimmed off, on true transverse
planes, to provide a neat, smoothly finished
article, and in order that such trimming op-
eration might be performed while the cone
was still on the mandrel, it has been pro-
30 posed to make the edge which is held in the
slot of the mandrel somewhat shorter than
the body of the cone, so that the trimming
might be done at points beyond the ends of
such edge or tongue. (See Smith Patent No.
35 886,884, dated May 5, 1908.)

This method, however, proved undesir-
able, for the reason that, in the finished
cone, the edge or tongue referred to, which
lies on the inside of the cone, did not ex-
tend the full length of the cone, but termi-
40 nated short of the base thereof. This pro-
duced a thin spot, which not only weakened
the structure, but resulted in a cone which
was slightly unbalanced, and which there-
fore tended to vibrate when rotated at high
45 speeds.

It has also been proposed to manufacture
cones from blanks having a deckle or feather
edge on the inside of the cone, for the pur-
pose of giving a well balanced uniform cone
50 with an exceptionally smooth interior.
While this method is highly desirable, from
a theoretical standpoint, it has been found
objectionable in practice, owing to the great
difficulty of properly gripping and holding
55 such a feather edge on the mandrel, and the
impossibility of preventing such an edge

from frequently becoming curled, puckered,
torn or otherwise distorted, thus producing
irregularities and resulting in many defec-
tive cones.

The present invention seeks to provide a
cone having all of the advantages of that re-
sulting from the deckle edge method, but
with none of the defects of such method, and
to this end I propose to construct a cone
60 from a blank having the edge which lies in-
side of the cone consisting partly of a deckle
or feather edge, and partly of an edge of
substantial thickness.

In this way, the deckle edge portion serves
70 to form a smooth and practically invisible
joint or seam near the base of the cone,
where smoothness is required, while, at the
same time, the thicker portion constitutes
a "tongue" which can be firmly engaged in
75 the usual slot of the winding mandrel, the
same as in the Smith patent above referred
to, and the necessity for attempting to grip
or hold the blank by a feather edge, with all
its attendant difficulties is thus obviated.
80

In order that the invention may be read-
ily understood, reference is had to the ac-
companying drawing, forming part of this
specification, and in which:—

Figure 1 is a diagrammatic perspective
85 view showing the method in which my im-
proved blank is placed upon the forming
mandrel;

Figure 2 is a view of the blank itself;

Figure 3 is a central vertical section
90 through a finished cone, showing the inside
joint; and

Figures 4 and 5 are horizontal transverse
95 sections substantially on the lines 4—4 and
5—5 of Figure 3.

Referring to the drawings in detail, and
more particularly to Figure 2 thereof, my
improved blank comprises a sheet of paper
A of substantially sector-shape. In fact, in
the embodiment shown, the blank is illus-
trated as being approximately half of a cir-
100 cle. It has a curved or arcuate edge *a* and
one of the radial edges *c* is preferably a
deckle or feather edge such as is usually
provided to form the outside joint or seam
105 of the cone.

In order to prevent an excessive amount
of material at the apex of the cone, I pref-
erably cut away the extreme central portion
of the blank, as indicated at *d*, and from
this point outward extends a substantially
110 radial edge or tongue *e*. This edge or

tongue does not, however, extend to the outer edge or periphery of the blank, but terminates at a notch *f*. Between this notch and the arcuate edge or periphery of the blank is disposed a laterally projecting portion or flap *B* having a relatively short free end *b* which is preferably radial, and which is thinned so as to provide a deckle or feather edge. In practice, the deckle edge *b* lies in the same straight line and forms a continuation of the deckle edge *c*. Thus my improved blank can be cut from a continuous sheet or web having one deckle edge, a portion of such edge being removed to form the tongue *e*. It will be understood that the edge of the tongue *e* is not a deckle edge, but is of substantial thickness, and may be the same thickness as the body of the blank.

20 In manufacturing cones from my improved blank, I employ a forming mandrel *X*, supported for rotation in any suitable way and provided along its longitudinal surface with a slot or groove *1*. This groove, however, preferably does not extend the full length of the cone, but terminates at a point *2* spaced from the small end of the cone a distance substantially equal to the length of the tongue *e*.

30 In practice, the tongue *e* is inserted in the slot *1*, as shown in Figure 1, by an endwise movement, until the end of the tongue adjacent the flap *B* abuts the end *2* of the slot. The portion or flap *B* beyond this point then occupies a position substantially tangent to the surface of the cone, as illustrated. It will of course be understood that the blank has been coated with adhesive in the usual manner, before being placed upon the forming mandrel, and after the tongue *e* has been positioned in the slot, as shown, the flap *B* is smoothed or pasted down upon the surface of the conical mandrel by any suitable means, such for example, as that shown in my co-pending application, Serial No. 60,794, filed October 6, 1925. Thereupon, the mandrel is caused to rotate and, by means of the usual or any suitable mechanism, the paper blank is pressed against the side of the rotating mandrel and is thus wound about the same to form a cone.

55 After being wound, the ends of the cone are trimmed by means of suitable cutters, one cutter operating past the small end of the mandrel and the other cutter operating in a circumferential groove *3* formed in the mandrel adjacent its large end, both cutters operating in true transverse planes. The cutters may be of the type shown in my co-pending application, Serial No. 691,288, filed Febray 7, 1924.

60 It will be observed that the groove *3* in which one of the cutters operates is located at such a point that the flap portion *B* of the blank overlies it. That is to say, the cutting

of the blank takes place within the confines of the flap portion and at a point well beyond the end *2* of the slot *1*, at which point a continuous unbroken surface of the mandrel is presented to the cutter so that the more or less irregular large end of the cone may be completely and effectively trimmed off.

70 Figure 3 shows the appearance of a finished cone after being trimmed by the cutters in the manner described. By reference to this figure, it will be seen that on the inside of the cone, extending from the small end longitudinally toward the base is a seam or joint formed by the edge of the tongue *e* but that this seam or joint does not extend entirely to the base of the cone. It terminates at the notch *f* and the space between this notch and the lower or large end of the cone is occupied by the flap *B* with its 80 thinned or deckle edge *d*.

75 By reference to Figure 4, the edge of the tongue *e* can be clearly seen, and by reference to Figure 5, the position occupied by the deckle edge *b* will be equally clear. An examination of this last mentioned figure shows how this deckle edge *b* of the flap portion *B* clings to the interior wall of the cone and merges into it, so as to produce a joint which is practically undiscernible or invisible and can scarcely be detected by the sense of touch. In other words, the interior of the cone at this point presents a substantially smooth unbroken continuous surface throughout its circumference.

80 In the common type of winding machines on which cones of this character are employed, the driving dog or spindle on which the cone is supported is so constructed as to fit snugly within the large end of the cone. Owing to the smooth interior surface of my improved cones, it fits such dog or spindle perfectly, and is accurately centered thereon so that, even when running at high speeds, it is remarkably free from vibration 100 or any unevenness of operation.

85 As the holding dog or chuck referred to extends only a comparatively short distance into the large end of the cone, the fact that there is a seam or joint formed by the edge *e* of the tongue of normal thickness is immaterial. By the use of this tongue, however, I am enabled to securely position the blank on the forming mandrel, as above described, in a simple and effective manner, 115 and thus, the necessity for attempting to hold or grip the blank by means of a deckle or feather edge, with all its attendant difficulties, is avoided. So far as I am aware, it is broadly new with me to provide a cone 120 made from a blank cut in such a manner that the finished cone has an inside joint formed in part of a tongue of substantial thickness and in part of a portion having a thinned or deckle edge, and by virtue of this con-

struction. I am enabled to produce substantially perfect cones in commercial quantities and with a very small percentage of defective cones.

5. What I claim is:—

1. A paper cone having on the inside the usual longitudinal joint extending from the small end toward the large end, but terminating short thereof, the interior surface 10 beyond said joint and adjacent the large end being substantially smooth throughout its circumference, and unbroken by any discernable joint.

2. A cone formed from a rolled paper 15 blank, such cone having a seam or joint on its inside, that portion of said seam or joint adjacent the large end being laterally offset from the other portion, and being substantially invisible so as to provide an unbroken 20 smooth surface, and that portion of the seam or joint adjacent the small end comprising an exposed edge of the blank of normal thickness.

3. A cone formed by rolling up a flat, substantially sector shaped paper blank having 25 at one of its radial edges an inner portion of substantial thickness, and an outer portion having a deckle or feather edge.

4. A blank for making cones, consisting of a substantially sector shaped paper sheet 30 having one of its radial edges cut to form a tongue of normal thickness, said tongue extending for only a part of the length of the radius from the apex of the sector, and a portion beyond said tongue having a deckle 35 or feather edge.

5. A blank for making cones consisting of a substantially sector shaped paper sheet 40 having at one edge a straight radial tongue, and between said tongue and the curved edge 45 of the sector, a flap projecting laterally of said tongue, and formed with a deckle edge at its free end.

6. A blank for making cones consisting of a substantially sector shaped paper sheet 45 having at one edge a straight radial tongue, and having the other radial edge deckled, said sheet also having, at a point between said tongue and the curved edge of the sector, a flap projecting laterally of said 50 tongue, and formed with a deckle edge at its free end, said deckle edge of the flap lying in substantially the same straight line as the deckled radial edge of the sector.

In testimony whereof I affix my signature.
PETER LE ROY McCALL.
